UNITED STATES PATENT OFFICE.

GEORGE MEYER, OF SEATTLE, WASHINGTON, ASSIGNOR TO LENA MEYER, OF SEATTLE, WASHINGTON.

CHAIN SAW.

1,387,605.

Specification of Letters Patent. Patented Aug. 16, 1921.

Application filed July 27, 1920. Serial No. 399,373.

To all whom it may concern:

Be it known that I, GEORGE MEYER, a citizen of the United States, and resident of the city of Seattle, county of King, State of Washington, have invented certain new and useful Improvements in Chain Saws, of which the following is a specification.

My invention relates to chain saws.

The object of my invention is to produce a chain saw of an improved type of construction, and particularly one which may be made of stampings, and in a manner of construction which will cheapen the cost thereof, and which will yet be thoroughly efficient, strong and reliable.

My invention consists of the novel parts and combination of parts which will be hereinafter described and then particularly pointed out in the claims.

In the accompanying drawings I have shown the construction of my device as I now prefer to make it.

Figure 1 is a side view of a few links of the saw, the side plate at one side being removed for certain of the links, to thus better show the interior construction.

Fig. 2 shows the manner in which the saw may be bent to pass the carrying and driving pulley.

Fig. 3 is a transverse section through the pivot of one of the links.

The saw is composed of two different kinds of links, one type carrying the teeth and the other serving as connecting links for the first kind. The teeth carrying links each consist of a tooth carrying plate 1, two side plates 2, and a filler bar 3. The tooth-carrying plate 1 consists of a straight base section having two thicknesses; the part 10, which is outside of the adjacent edge of the side plates 2, is thicker than the web 11, which lies between the edges of the side plates. The side plates 2 are of a thickness such that when secured to the tooth carrying plate 1 the outer surfaces will be flush. These plates are secured together in any suitable manner, as by use of rivets 12.

At the opposite edge of the side plates 2 is a filler bar 3. The inner edge of this filler plate 3, or that edge which contacts with the wheels over which the chain runs, and the inner edges of the side plates 2 adjacent thereto, should be convexly curved, as shown at 32, in order that it may fit snugly upon the supporting wheel A, and in order to obviate any tendency for one edge

of the link to cock up and throw the chain from a true straight line. This plate 3 is also secured by rivets or any other suitable means. A spacing washer 4 is also placed between the side plates 2, and the side plates are secured thereto by means of a rivet 40.

Each of the teeth carrying plates above described are secured to form a chain by the connecting links 5. These connecting links are of a thickness to enter the space between the two side plates 2. They are provided with holes which fit over the spacing washer 4, the two links being so proportioned that when secured together the adjacent edges of the teeth carrying links abut. This is illustrated in Figs. 1 and 2.

The teeth carrying plates 1 are offset lengthwise of the chain with relation to the other parts of their link, as is clearly shown in Fig. 1. This causes one end of the tooth carrying plate to project beyond the end edges of the side plates 2, while the other end of the tooth carrying plate is back from the adjacent end, each of the plates 2 thus forming a recess into which enters the projecting end of the tooth carrying plate of the adjacent link; this further interlocks the links to prevent twisting thereof.

The outer edges of the connecting links 5, meaning thereby the edges which are toward the toothed edge of the chain, have their central portions 50, or that portion which extends between points opposite the chain pivots, straight and parallel with the line connecting the pivot centers. Immediately outside of these points the outer edge of the link has a short curved sector 51 having its center of curvature at the pivot center of the links. Outside of this curved sector 51 is a tangent 52 which extends to the end of the link. The extent of the curved sector 51 and the angle which the tangent edge 52 makes with the line connecting the pivot centers, depends upon the bending angle 100 which is desired in order to pass the same about the guiding and driving pulleys.

The inner edge of the connecting links 5, toward their outer ends, have a bearing upon the filler bar 3, as is shown in Fig. 1. This edge of the connecting links is cut away, as shown at 53, so as to permit swinging of the links when the same is bent. When, however, the chain has reached the limit of its bend in this direction, I prefer to have it contact with the outer ends of the filler bars 3 so as to prevent further bending. As an

alternative form of construction the inner edge of the links 5 may be made straight, as is shown at 54 in Fig. 1, and the inner edges of the filler bar 3 may be beveled, as shown at 30. To permit inward bending it is also necessary to cut the inner corner of the side plates 2, as is shown at 20. The angle of this cut will determine the maximum bending of the chain in this direction. I prefer 10 to have the cut such that when the maximum bending movement has taken place these edges will come in contact. To best secure this result the edges 20 should be connected with the edges 22, which are in contact when 15 the chain is straight, by a short curved sector 21, to which the two edges 20 and 22 are tangent.

This chain, it will be seen, is composed of parts of such character that they may be all 20 cut from sheet metal without further work, excepting the tooth carrying plate 1. This plate has an inner web section 11, which is thinner than the body thereof. This may, however, be cheaply formed as a drop forging. The parts may, therefore, be cheaply 25 made, and also cheaply assembled, also the different parts may be made of material having different characteristics and qualities, if this be desired. In consequence, of 30 this, the saw may be cheaply made and also readily repaired and kept in good working condition.

What I claim as my invention is:

1. A chain saw comprising one set of links 35 each composed of a toothed plate, two side plates overlapping the inner edge of the toothed plate and a filler plate between the opposite edges of the side plates, and another set of connecting links entering between the side plates, pivots connecting the connecting links and said side plates, the inner edge of the toothed plate and the outer edge of the links being engaged at 40

the ends of said toothed plates when the chain sections are in a straight line, the 45 outer edge of the connecting links having a curved sector which maintains substantial engagement with the inner edge of the toothed plate when the chain bends inward and a tangent extending from said curved 50 sector and engaging the inner edge of the toothed plate to limit the inward bending of the chain.

2. A chain saw comprising one set of links each composed of a toothed plate, two side 55 plates overlapping the inner edge of the toothed plate and a filler bar between the opposite edge of the side plates, and a set of connecting links entering between said side plates and pivots passing through said links, the adjacent ends of the teeth carrying links outwardly of their line of pivot centers abutting when the chain is straight, the outer edge of the connecting link having a section which when the chain is straight engages 65 the inner edge of the toothed plate at the ends thereof the inner edge of the connecting links at the same time engaging the edge of the filler bar toward its center to further prevent bending of the chain in one direction beyond a straight line.

3. A chain saw as in claim 2 in which the outer edges of the connecting links are cut away at their ends and the adjacent edges of the connecting links and the ends of the 70 filler bars are cut to permit bending in one direction.

4. A chain saw as in claim 2, in which the tooth carrying plates are displaced lengthwise of the chain with relation to the side 80 plates to form a recess at one end and a projection at the other to enter the recess in the adjacent link.

Signed at Seattle, Washington, this 19th day of July, 1920.

GEORGE MEYER.
